DESIGN FOR A FOLDING HOUSE VEHICLE OR SIMILAR ARTICLE

Nettie E. Graven, Wooster, Ohio

Application September 7, 1945, Serial No. 121,911

Term of patent 14 years

(Cl. D14—3)

To all whom it may concern:

Be it known that I, Nettie E. Graven, a citizen of the United States, residing at Wooster, in the county of Wayne and State of Ohio, have invented a new, original, and ornamental Design for a Folding House Vehicle or Similar Article, of which the following is a specification, reference being had to the accompanying drawings, forming part thereof.

Fig. 2 is a side perspective view thereof;

Fig. 3 is a front view thereof; and

Fig. 4 is a rear view thereof.

Both sides of the vehicle design are similar except for the door entrance with the steps and hand rail, as shown in Figs. 1 and 2.

I claim:

The ornamental design for a folding house vehicle or similar article, substantially as shown and described.

NETTIE E. GRAVEN.
